(57) **CLAIM**

The ornamental design for a cover pad for a clothes hanger, as shown and described.

DESCRIPTION

FIG. 1 is a front elevation view of a cover pad for a clothes hanger embodying the new design, the rear elevation view being a mirror image of the front side as shown;

FIG. 2 is a top plan view thereof;

FIG. 3 is a bottom plan view thereof;

FIG. 4 is a right end elevation view thereof; the left end being a mirror image of the right end as shown;

FIG. 5 is a transverse sectional view taken generally on the line 5-5 of FIG. 2;

FIG. 6 is a vertical sectional view taken generally on the line 6-6 of FIG. 5;

FIG. 7 is a vertical sectional view taken generally on the line 7-7 of FIG. 5; and,

FIG. 8 is a sectional view taken generally on the line 8-8 of FIG. 5.
